The ornamental design for a child safety seat for motor cars, as shown and described.

DESCRIPTION

1. Child safety seat for motor cars

1.1 is a perspective view of a child safety seat for motor cars in accordance with the present invention;

1.2 is a front elevational view of the child safety seat for motor cars of 1.1;

1.3 is a rear elevational view of the child safety seat for motor cars of 1.1;

1.4 is a side elevational view of a first side of the child safety seat for motor cars of 1.1;

1.5 is a side elevational view of a second side of the child safety seat for motor cars of 1.1;

1.6 is a top plan view of the child safety seat for motor cars of 1.1; and

1.7 is a bottom plan view of the child safety seat for motor cars of 1.1.

The broken lines in the drawings depict portions of the child seat for motor cars that form no part of the claim.
